UNITED STATES PATENT OFFICE.

ROBERT B. WHEELAN, OF BROOKLYN, NEW YORK.

LOUD SPEAKER.

Application filed March 29, 1924. Serial No. 702,708.

This invention relates to an improved loud speaker, the utility of which will not be limited to the projection of sound waves.

It is an object of this invention to provide 5 a device of the character stated which will evenly distribute the sound waves and which will possess a mellow tone.

A further object is that of furnishing a loud speaker which will present an ornamental and pleasing appearance.

An additional object is that of providing 10 an object of the nature aforementioned which will efficiently perform the purpose for which it is intended and which will also 15 be economically and readily manufactured and assembled.

The invention accordingly comprises an article of manufacture possessing the features, properties, and the relation of elements which will be exemplified in the article hereinafter described and the scope of 20 the application of which will be indicated in the claim.

For a fuller understanding of the nature 25 and objects of the invention reference should be had to the following detailed description taken in connection with the accompanying drawing, in which:

Figure 1 is a partly sectional side elevation of one form of loud-speaker which may be manufactured within the terms of the 30 present invention.

Fig. 2 is an end view of the amplifying portion of the loud speaker as shown in 35 Fig. 1.

Fig. 3 is a fragmentary sectional side view of another form of the invention.

Fig. 4 is a sectional plan view taken along the lines 4—4 and in the direction of the arrows as indicated in Fig. 3.

Fig. 5 is a view similar to Fig. 3, but showing still another form of loud speaker.

According to its preferred form, the invention includes the thought of a lamp of 45 more or less conventional construction, modified in certain particulars, however, so that while it retains its ornamental and useful qualities, it may additionally be employed as a loud speaker which will have a mellow and pleasing tone, and will faithfully render various acoustical effects.

Thus, as in Fig. 1 it will be seen that in accordance with conventional construction, the lamp may include a base 10, to which 50 is attached a standard 11, conveniently having a vase-like appearance, and which stand-

ard supports adjacent its upper end, and preferably in manners hereinafter set forth, an illuminating element such as an electric bulb 12, as well as a suitable shade 13.

However, contrary to conventional construction, it will be perceived that the lower end of the standard 11 is enlarged to provide a casing 14, which in the present instance receives a loud speaking unit, the action 60 of which, if desired, may be regulated in any preferred manner, as for example by means of mechanism controlled by a dial 15. Thus, it being understood that the loud speaking unit is connected with any desirable "output" by means of wires (not shown), this unit will act to project sound waves through the whole body of the standard.

Now, with a view of supporting the bulb 75 12, as well as the shade 13, it will be noted that it is preferred that a plate 16 be utilized, which is provided with a socket 17 in its upper face for the reception of the bulb, this plate being mounted at the upper end 80 of the standard 11, and having its outer edges bearing against the inner face of the shade, and if desired, the body of the plate may be of transparent material so that no interference will be encountered by the 85 downwardly projecting light rays emanating from the bulb.

In order to efficaciously conduct the sound waves from within the amplifier provided by the standard 11, and to evenly distribute 90 the same from the loud speaker, it will be noted that in the present instance, i. e., Fig. 1, the upper edges of the standard 11 are notched, as at 18, so that there are spaces extant between the under face of the plate 16 and certain of the upper edges of the standard. Also the plate, preferably has its under face of a concavo-convex form so as to provide a sound deflector, it being thus understood that the sound waves originating 100 in the loud speaker unit will be conducted through the standard and amplified therein, after which they will be deflected by the stem on the under face of the plate so as to be evenly distributed against the entire inner surface of the shade 13, which in itself 105 will act as a horn.

Referring to the construction shown in Figs. 3 and 4, it will be noted that similarly to the construction aforescribed, a standard in the nature of an amplifier 19 is employed, and a band 20 is suitably secured 110

to the outer face of this standard adjacent its upper end, this band acting as a support for sockets 21, mounting bulbs 22, as well as supporting a plurality of radially extending arms 23, which mount a shade 24, together with a suitable sound deflector 25.

It will be appreciated that this type of loud speaker will have virtually the same characteristics, and be equally efficient to that 10 described in the preceding figures and referring finally to the construction shown in Fig. 5, it will be noted that in that form of the invention the bulb 26 is carried in a socket 27, which is mounted upon brackets 15 28, suitably attached to the upper end of the standard or horn 29, and a spider 30 may be used which bears against the body of the bulb and in turn mounts a shade 31 on the inner face and adjacent the upper end of 20 which a suitable sound deflector 32 is provided.

It will be understood that all of the foregoing parts may be made of any desirable material, but it is preferred, that while the 25 standard may be of wood, iron, vitreous material, etc., etc., that the horn of the loud speaker, i. e., in the present instance the shade portion of the lamp, shall be of parchment or similar material. By the use of a 30 substance of this nature it has been found that extremely mellow and pleasing acoustical effects are produced, and where constructions similar to those shown in the illustrations are employed, it will be understood 35 that due to the forms adopted, the sound waves will be distributed radially and evenly so that the acoustical effects may be heard throughout the entire room in which the loud speaker may be situated. Also it will be ap-

preciated that the supporting surface against 40 which the lamp is placed will act as a distributor of the sound waves in that in addition to their being projected in radial directions, they will also be projected against the supporting surface adjacent which the lamp 45 is situated.

From the foregoing, it will be understood 50 that the objects of this invention have been accomplished and it will be appreciated that since certain changes and different embodiments of the invention could be made without departing from the scope thereof, that it is intended that all matter contained in the above description or shown in the accompanying drawing shall be interpreted as 55 illustrative and not in a limiting sense.

Having described my invention, what I claim as new and desire to secure by Letters Patent, is:

A loud speaker, including a base, a standard extending upwardly from said base, a downwardly-extending shade spaced from and positioned adjacent the upper end of said standard and extending toward said base, and a sound-deflecting element associated with said shade and extending from a point centrally above the upper end of said standard to points adjacent the inner faces of said shade, said base being hollow and receiving a loud speaker unit, said standard having a bore connected with said base, and said shade acting as a horn directing the sound waves emanating from said unit and passing through the standard bore against the surface supporting said base. 65 70 75

In testimony whereof I affix my signature.

ROBERT B. WHEELAN.
